UNITED STATES PATENT OFFICE.

ANDREW THOMA, OF CAMBRIDGE, MASSACHUSETTS, ASSIGNOR TO NORTH AMERICAN CHEMICAL COMPANY, OF BOSTON, MASSACHUSETTS, A CORPORATION OF MAINE.

SHOE-BOTTOM-FILLING MACHINE.

1,310,588.

Specification of Letters Patent. Patented July 22, 1919.

Application filed June 11, 1918. Serial No. 772,979.

To all whom it may concern:

Be it known that I, ANDREW THOMA, a citizen of the United States, and resident of Cambridge, in the county of Middlesex and 5 State of Massachusetts, have invented an Improvement in Shoe-Bottom-Filling Machines, of which the following description, in connection with the accompanying drawings, is a specification, like letters on the 10 drawings representing like parts.

My present invention is an improvement on the class of machines disclosed in the Arnold Patent No. 808,227 of December 26, 1905, and my Patent No. 937,393 of May 15, 1910, in which a normally semi-solid or self-contained loaf or fragment of filler is subjected to a slow melting heat and then placed in the shoe-bottom cavity and condensed or unified therein by a super-heat 20 under pressure. This invention is limited to shoe manufacture.

The kind of filler in question (for instance, that considered in my Patents Nos. 808,224, 832,002, and 861,555) is very slow 25 to melt, inasmuch as the composition is heat-resistant, and the loaf or package is so dense that the outside portion thereof insulates the inside against the penetration thereof by the heat. On the other hand, 30 modern shoe-factory practice requires high speed on the part of the operators. A further difficulty is found in the fact that this filler cannot be subjected to an extreme heat, lest, while the interior of the mass is being 35 melted, the exterior will char or burn,—so that a relatively low heat is necessary for the proper melting of the filler. Accordingly my present invention aims to provide an apparatus especially adapted to take care 40 of these two requisites, viz. quickness of supply for the operator and natural slowness of preparedness on the part of the material. In the preferred embodiment of my invention as herein shown, I have illustrated 45 my invention in connection with electric heating means.

The first feature of my invention to which I especially direct attention is the provision of means for affording two entirely independent degrees of heat, or at least two heating media capable of variable and independent regulation, thereby rendering it possible to have a heat of large volume but low intensity for melting the filler mass and keep-

ing the same in proper melted condition 55 without danger of burning or injuring the filler and yet with an assurance that the filler will be melted as quickly and thoroughly as its nature permits. At the same time a more intense heat is provided for the 60 super-heating tool and for maintaining the applying knives or spatulas at the desired relatively high heat. The second feature of my invention meriting special remark is the provision of means for utilizing the radiant 65 heat (which would otherwise be wasted) for the preliminary softening of the filler and at the same time keeping the external apparatus relatively cool so as not to interfere with the operator. This double object is 70 secured by inclosing the first-mentioned larger heating medium in an auxiliary casting or receptacle for the preliminary softening of the filler, so shaped and located that the natural position of the filler therein 75 serves to bar the exit of the heat, or in other words prevents the radiation of the heat from the receptacle and thereby maintains the latter much cooler than would otherwise be the case, and hence is more pleasant to 80 the operator by eliminating this serious objection to the former types of apparatus. Further features of my invention relate to the convenience and facility of use and strength and simplicity of construction. 85 Details of all these various features will be pointed out in connection with the accompanying drawings, in which I have shown a preferred embodiment of the invention.

In the drawings,

Figure 1 is an enlarged vertical cross-sectional view of the apparatus, partly broken away for clearness;

Fig. 2 is a view thereof in side elevation, looking at the right hand side, parts being 95 broken away;

Fig. 3 is fragmentary perspective view of the apparatus; and

Fig. 4 is a top plan view of the apparatus as shown in Figs. 1 and 2.

As herein shown, the apparatus is rectangular in its general construction, and is intended to have the operator stand at one end, the apparatus being supported on four legs 1 secured at their upper ends in a heavy 105 top or frame casting 2 which directly supports the upper section 3 and indirectly the lower section 4. The upper section com-

prises a tank or pot whose forward end 5 contains the fully melted filler in convenient position to be dipped out by the operator by means of a knife or spatula, such for instance as shown in the aforesaid Patent No. 808,227 or in my later Patent No. 957,893, to be deposited in the shoe-bottom. This pot corresponds most nearly to the dip-pot 10 of said Patent No. 808,227. The rear portion 6 of said tank constitutes a supply chamber. Here the softened or partially melted filler loaves are deposited by the operator in the presence of the confined heat beneath the cover 7 until needed for use. 10 The operator then raises the cover 7 on its hinge 8 and pokes forward into the end 5 a portion of the filler from the end 6, which filler has now become thoroughly softened. The forward end of the cover 7 extends 20 downwardly as shown at 9 to constitute a movable partition for holding the front portion of the filler in a proper collected body in the part 5 for the convenience of the operator and at the same time confining all 25 the heat possible within the end 6 for the more rapid melting and disintegrating of the filler loaf which has been placed therein. The tank which contains the portions 5 and 6 is heat jacketed, having for this purpose 30 an outside wall 10 and bottom 11 forming a heater pocket with an opening 12 at one side for the ready insertion and removal of a heating plate 13 of suitable electric resistance wire embedded in enamel in well 35 known manner. For the convenient removal of this plate 13 and also to limit its insertion, it is provided at its outer edge with a downturned handle 14 which strikes against the bottom 11 when the plate is in position. 40 The bottom 11 of the upper section 3 or tank portions 5, 6 is shown as provided with a series of perforations 15 through which the surplus heat passes, and which also serve the purpose of promoting heat circulation 45 and therefore increasing the free radiation of heat from the plate 13. This heat, and also the heat which radiates from the bottom 11, maintains a moderate heat in the lower chamber or section 4. This section is 50 capable of receiving preferably several loaves of filler laid on its bottom and accessible to the operator through a hinged side or door 16 secured to the upper tank by hinges 17 and provided with a latch 18 at 55 its lower end when the lower section 4 is to be closed. The legs 1 of the apparatus are secured rigidly at the four corners of the tank or section 4 as indicated at 19, thereby increasing the stability of the apparatus. 60 The resistance heater 13 is operated externally by a switch 20 located conveniently for the operator at the front end of the section 3 and preferably of a three-switch construction so as to afford a current-off position, medium heat, and maximum heat. 65

Mounted conveniently for the operator, herein shown at the left hand side of the frame 2, is an upright 21 and a horizontal tubular arm 22 at whose right hand end is a roll 23, adjacent which is a knife block 24 (corresponding in a general way to the roll 13 and knife block 23 of said Patent No. 808,227), and these are heated by a resistance coil inserted in the horizontal tubular support 22 and regulated by a switch 25. By having 70 the unifying and spreading superheater 23 in the form of an overhanging or freely projecting tool rigidly related to the pot, and with a predetermined heat relative thereto, it greatly facilitates the speed, ease, 75 and thoroughness of the work.

In use, the operator keeps several fresh loaves of filler in the lower section 4 or preliminary-softening oven and a supply of melting filler in the end 6 of the upper tank, 80 while he uses the melted filler from the end portion or dip pot 5. The operator stands at the end of the machine adjacent the switch 20, and by means of the latter regulates the heat in the parts 3 and 4 to that degree of intensity which the filler will stand without danger. He turns on more heat, however, at the switch 25 for the roll 23 and knife block 24 than would be practicable to use in 85 the rest of the apparatus. As he dips up 90 the filler from the tank 5 and deposits the desired amount in the shoe-bottom with the spatula as explained in the prior patents above mentioned, he quickly moves the filled shoe beneath the roll 23 and thereby spreads 95 and unifies the filler properly in the shoe-bottom under the super-heating influence and pressure of the roll. As this superheating effect is momentary only, there is no danger of injuring the filler, and yet the cementitious binder portion of the cork filler is momentarily melted over the surface of the filled bottom to just that degree necessary 100 for properly filling the corners and giving the desired waterproofing effect to the inseam of the innersole. Having used most of the melted filler from the dip pot 5 portion 105 of the tank, the operator quickly lifts up the cover 7 and now finds that the loaf contained in the subjacent part 6 is fully disintegrated 110 and ready for use in the part 5. He pulls forward some or all of said loaf by the aid of his knife or spatula and then opens the door 16 of the part 4 and takes one of the softened loaves from said part or section 4 115 and places it in the part 6, replacing it in the oven 4 by an entirely fresh loaf. As the melting part 6 is subjected continuously to a relatively high heat, the softened loaf is quickly disintegrated and is sure to be ready 120 for the operator as soon as he has used up the filler contained in the dip portion 5 of the tank.

The advantages of my invention will be obvious from the foregoing description. 130

Notwithstanding the fact that the loaf cannot be heated repeatedly or quickly or highly lest it be burned, and cannot be penetrated rapidly even by a strong heat, my apparatus 5 makes it feasible to use this kind of filler with extreme rapidity. The cold solid loaf is placed in the preliminary-softening chamber 4 and subjected to a mild but continuous heat for a relatively long period of time, and 10 this heat gradually penetrates farther and farther into the mass until the loaf is moderately softened throughout. By this time the melting chamber 6 has been emptied as the operator rapidly fills shoes therefrom, 15 and the softened loaf is now transferred to the latter, in whose confined rear inclosure the loaf is subjected to the highest degree of heat that it can stand. As, however, it is already in a soft condition and therefore more 20 accessible to the heat, the latter crumbles it and melts it rapidly, so that it is fully melted and ready for the forward end 5 of the tank as soon as the latter is ready to receive it. All this is accomplished by the same relatively 25 low-heat radiating medium 13. The preliminary softening is accomplished by that portion of the heat which would otherwise be wasted, and the apparatus is so constructed and arranged that this preliminary heating is accompanied by the further advantage of serving as a means for maintaining the apparatus comparatively cool externally (as compared with the hot pots of the Arnold machine). Notwithstanding the low 30 heat at which the apparatus may be run, the separately heated roll 23 makes it possible to carry out the requirements of shoe-bottom filling with that despatch which is demanded by modern high-speed practice. It 35 is this necessity for despatch, and the exacting peculiarities of the filler and the fact that this work is usually done by boys, which, together, make the problem difficult. The superheating of the filler so as to accomplish 40 the waterproofing effects to the best advantage is taken care of in my present machine even better than in the Arnold machine, by combining three features of advantage, namely; the provision of a controlled 45 high heat for the superheater or unifying and spreading member 23, having this tool project freely so that the operator can manipulate the shoe with great freedom of movement of his arms (the right hand usually 50 grasping the toe and the left hand grasping the cone of the last), and providing a contiguous heating means for the filler in such position, relation and construction that the filler is brought to exactly the right condition, and there maintained in instant 55 readiness to be deposited in the shoe bottom. The relation of the parts contributes to (1) rapidity of shoe filling, (2) absence of fatigue of the operator, due to the position, construction and heat control of the block or roll 23 60 and its rigid mounting close to the pot, so that boys can do the work; (3) condensing of the filler in the shoe bottom (due to the fact that the filler is in exactly the right condition when deposited from the pot into the 65 shoe and the further fact that the parts of the machine are so related that the shoe then receives the heat pressure instantly); (4) insuring a superior sticking of the filler by reason of the special penetrating quality 70 which the filler has when hot, but does not have when it begins to stiffen; (5) the spreading of the filler body laterally to occupy the crevices of the inseam, largely due to the facility for instantly applying the 75 shoe to the rigid heat block and with the right direction of pressure before the filler has chilled against the cold, wet leather; (6) the waterproofing resulting from the top-surface spreading of the binder, which could 80 not be as efficiently effected but for this special combination and relation of parts and heat control; (7) heat economy and heat uniformity, which are due to the juxtaposition of the pressure block or roll, pot, and 85 knife-heater, and the separate controls 20, 25 and heat inclosing jacket or wall 10, and (8), the superheating effect, which is due to the suddenness of the fluidifying of the binder at the critical moment (under the right heat, 90 correct direction of pressure, and facilitated back and forth quick movement), to the fact that the mass temperature of the block or roll may always be maintained higher than the 95 filler, and the close relation of the roll (on its rigid mounting) to the pot or tank 5.

Having described my invention, what I claim as new and desire to secure by Letters Patent is:

1. A shoe-bottom filling machine, comprising a heated filler receptacle for shoe filler, a heated unifying and spreading member in close, fixed and rigid relation to said receptacle for the quick filling of a shoe with the hot filler and the immediate superheating, 105 unifying and spreading of said filler by the heated member, separate heating means for said receptacle and said spreading member, and regulating devices for independently varying the heat in said receptacle and said 110 spreading member.
2. A shoe-bottom filling machine, comprising a heated filler receptacle for shoe filler, a heated unifying and spreading member in close, fixed and rigid relation to said 115 receptacle for the quick filling of a shoe with the hot filler and the immediate superheating, unifying and spreading of said filler by the heated member, a removable electric heater for said receptacle, a stationary regulating switch for varying the heating effect of said heater, an electric heater for said 120 fixed spreading member, and a separate regulating switch for said last mentioned heater.

3. A shoe-bottom filling machine, comprising two superposed wholly separated sections, one containing a delivery tank for the melted shoe filler and the other containing a preliminary-softening chamber, and a heater common to said two sections arranged to maintain a low heat in the softening chamber and a relatively high heat in the tank.
- 10 4. A shoe-bottom filling machine, comprising two superposed sections, one containing a delivery tank for the melted shoe filler and the other containing a preliminary-softening chamber, and an adjustable heater located between and separating said two sections and maintaining different degrees of heat in the two sections.
- 15 5. A shoe-bottom filling machine, comprising a delivery tank having an inclosing hot-air jacket for holding the shoe filler, and an electric heater in the bottom portion of said jacket, and a preliminary-softening chamber below said tank and embracing the bottom thereof for receiving the radiant heat from the latter, whereby a low heat is maintained in the chamber and a high heat in the jacket and means for regulating said heat.
- 20 6. A shoe-bottom filling machine, having a depending melting tank for holding the shoe filler, a heat jacket partially surrounding the depending portion of said tank for maintaining a relatively high heat therein, said jacket having a heater pocket in its lower portion beneath said tank, a removable heater for said pocket, and an enclosure, contiguous to said heater pocket forming a preliminary softening section for receiving fresh batches of filler to be softened, said heater pocket having its inside provided with perforations for the surplus heat from said jacket to pass directly into said preliminary softening section.
- 25 7. A shoe-bottom filling machine, comprising a tank adapted to shoe filler, having a forward delivery portion and a rear melting portion and a cover for the latter, hinged adjacent the rear end of the tank, to cover said rear portion and provided with a depending forward end to separate said rear portion from said delivery portion.
- 30 8. A shoe bottom filling machine, comprising a tank adapted to shoe filler, having a forward delivery portion and a rear melting portion and a cover for the latter, hinged adjacent the rear end of the tank, to cover said rear portion and provided with a depending forward end to separate said rear portion from said delivery portion, said depending forward end being curved approximately on the arc of a circle from the pivot point as a center to facilitate the easy forcing of said end through the mass of filler to the bottom of the tank for the convenient closing of said rear portion to promote the heating of the filler therein.
- 35 9. A shoe bottom filling machine, comprising a heating pot for the shoe filler, having an open delivery end, a unifying and spreading tool mounted to overhang said delivery end, said tool being rigidly supported at one side of said pot, and from one end only, thereby leaving the tool projecting freely for the convenient handling of a shoe by the operator with reference to said tool and pot, and heating means within the tool support having control independent of the pot, whereby a higher regulable heat may be maintained in the tool than in the filler contained in the pot.
- 40 10. A shoe bottom filling machine, comprising a filler heater for maintaining a supply of shoe filler in proper heated condition, a unifying and spreading tool mounted rigidly at one end only close to said filler heater, said tool having free space all around the other end, and a knife-block mounted adjacent said tool and provided with a slit in the mass of the block for receiving the blade of the knife.
- 45 In testimony whereof, I have signed my name to this specification, in the presence of two subscribing witnesses.

ANDREW THOMA.
